FOLDING DEVICE FOR CARRIAGES, APPLI-
CABLE IN PARTICULAR TO PERAMBU-
LATORS

Paul Ollagnon, Saint-Etienne, France

Application February 5, 1948, Serial No. 6,524
In France October 9, 1946Section 1, Public Law 690, August 8, 1946
Patent expires October 9, 1966

6 Claims. (Cl. 280—42)

1

The object of the invention is to provide a hand-propelled carriage of light construction, all the parts of which can be rapidly folded into a small space to enable it to be readily transported.

By way of example, a perambulator of the push-chair type will hereinafter be described, but it is to be understood that the invention is equally applicable to all types of two-wheel or four-wheel carriages.

In the accompanying drawings, which are not intended to constitute any limitation:

Figure 1 is an external elevational view of a perambulator constructed in accordance with the invention, in the open position ready for use;

Figure 2 is an external plan view corresponding to Figure 1;

Figure 3 shows the perambulator in the folded position;

Figure 4 is an external half-view in profile, as seen from the steering end;

Figure 5 is a diagrammatic view of the perambulator on a smaller scale, the dot-and-dash lines representing the position of the folded panels, and

Figure 6 is a plan view corresponding to Figure 5, the dot-and-dash lines again representing the position of the folded panels.

The device illustrated comprises essentially two independent vertical panels A and B supporting the wheels, which may or may not be resiliently suspended and are situated in the same planes as the panels, the said two panels being connected together by two pins C and D secured to the base of the centrally disposed handle E used for propelling the carriage.

The said pins C and D, which are parallel to one another and to the plane of the panels A and B, are so disposed that:

(1) They coincide with the bisector $x-y$ of the angle θ formed on the profile of the carriage by the line of the upper edge of the panels A and B on the one hand and by the line of the handle E on the other hand.

(2) They are symmetrically articulated to the base of the handle E by a T-shaped coupling member F and to each of the panels A and B by two coupling members G and H which fulfil the following conditions: the width m of the coupling member F, added to the sum of the equal widths (n, o) of the coupling members G and H, is equal to the total width p or track of the carriage.

The equal widths n and o of the coupling members G and H are each equal to one half of the width m of the coupling member F of the handle E.

2

Under these conditions, the folding device functions in the following manner:

The carriage being in the unfolded position, that is to say, ready for running, if the two panels A and B are hinged back in the direction of the arrow R so as to describe a semi-circle about the pins C and D, the following result will be obtained:

(a) The upper edge of each panel A, B will 10 take up a position parallel to the handle E (angle $\alpha=\angle\beta$).

(b) The upper edge of each panel A, B will be brought against the handle E ($n=\frac{1}{2}m$ and $o=\frac{1}{2}m$).

(c) The panels A and B, after having described a semi-circle, will again become parallel to one another and to the handle E (the pins C and D being parallel). Figs. 5 and 6 show diagrammatically on a reduced scale the relative position 20 of either vertical panel with reference to the handle E supposed to retain a permanent angular position. The panel illustrated in solid lines corresponds to its operative position with reference to the handle while the dot and dash illustration of the panel corresponds to its folded inoperative position alongside of the handle after pivoting round the axis $x-y$ lying in a plane at mid-distance between the parallel vertical planes passing through the handle and the panel considered.

Thus the two panels A and B and the handle E will be connected together in the axis of the handle E, so that the carriage can readily be transported.

It is to be noted that in the open position two 30 stops I and J limit the rotation of the panels A and B about their pins C and D and retain them parallel to the handle E.

A seat K independent of the vehicle and constituted by straps or light folding panels is secured 40 to the panels A and B and to the coupling member F.

The arrangements is completed by a tie rod L drawing the two panels A and B towards one another in the opening position and securing the whole arrangement in this position.

It will readily be seen that the folding device hereinbefore described, while being of simple construction, is strong and light, it being understood that the parts not described will be employed in 50 the known manner.

It will be understood from the foregoing that the invention is in no way limited to the embodiment or to the constructional form of the parts more particularly described, but covers all modifications thereof.

I claim:

1. A foldable carriage comprising two independent laterally spaced vertical panels, individual wheels supporting each panel substantially in the vertical plane thereof, a single centrally disposed control handle located obliquely with reference to horizontality in a vertical plane at equal distances from the two vertical panels and a pivotal connection between each panel and the handle on which said panel is adapted to swing between two positions parallel to the handle round an axis lying in a vertical plane at equal distances from the vertical plane of the corresponding panel and from the vertical plane passing through the handle, said axis lying in vertical projection along a line equiangularly disposed relatively to a horizontal line and to the direction of the handle.

2. A foldable carriage comprising two independent laterally spaced vertical panels, individual wheels supporting each panel substantially in the vertical plane thereof, a single centrally disposed control handle located obliquely with reference to horizontality in a vertical plane at equal distances from the two vertical panels, a horizontal bar rigid with the handle extending perpendicular to either side thereof a distance equal substantially to one half of the distance separating said handle from either panel and a lateral projection rigid with one end of either panel and pivotally secured to the corresponding free end of said bar round an axis lying in the vertical plane passing through said free end and parallel to the panels, the direction of the pivotal axis in said vertical plane coinciding substantially with a line equiangularly disposed relatively to a horizontal line and to the angular direction in space of the handle in its operative position.

3. A foldable carriage comprising two independent laterally spaced vertical panels constituted each by an incurved tubular member, individual wheels supporting each panel substantially in the vertical plane thereof, a single centrally disposed control handle located obliquely with reference to horizontality in a vertical plane at equal distances from the two vertical panels and a pivotal connection between each panel and the handle through which said panel is adapted to pivot round an axis lying in a vertical plane substantially along a line equiangularly disposed relatively to a horizontal line and to the direction of the handle, stops rigid with the handle limiting the outward movement of said panels when moved away from the handle towards their operative position and a removable spacing rod engaging the rear ends of the panels for holding same in their operative spaced position.

4. A foldable carriage comprising two independent laterally spaced vertical panels, individual wheels supporting each panel substantially in the vertical plane thereof, a single centrally disposed control handle located obliquely with reference to horizontality in a vertical plane at equal distances from the two vertical panels, a horizontal bar rigid with the handle extending to either side thereof a distance equal substantially to one half of the distance separating said handle from either panel, a lateral projection rigid with one end of either panel and pivotally secured to the corresponding free end of said bar round an axis lying in the vertical plane passing

through said free end and parallel to the panels, the direction of the pivotal axis in said vertical plane lying substantially along a line equiangularly disposed relatively to horizontality and to the angular direction in space of the handle in its operative position, a spacing rod removably holding the panels in their operative spaced position and a yielding seat removably secured between the two lateral panels and adapted to engage the spacing member and horizontal bar system.

5. A foldable carriage comprising two independent laterally spaced vertical panels, individual wheels supporting each panel substantially in the vertical plane thereof, a single centrally disposed control handle located obliquely with reference to horizontality in a vertical plane at equal distances from the two vertical panels, a horizontal bar rigid with the handle extending to either side thereof a distance equal substantially to one half of the distance separating said handle from either panel, a lateral projection rigid with one end of either panel and pivotally secured to the corresponding free end of said bar round an axis lying in the vertical plane passing through said free end and parallel to the panels, the direction of the pivotal axis in said vertical plane lying substantially along a line equiangularly disposed relatively to horizontality and to the angular direction in space of the handle in its operative position, a spacing rod removably holding the panels in their operative spaced position, a yielding seat removably secured between the two lateral panels, casings secured to the front and to the rear of each vertical panel and adapted to pivotally carry the wheels in the plane of said panels, and yielding means connecting the wheel carrying casings to hold the wheels in the vertical plane of the corresponding panel.

40 6. A foldable carriage chiefly for use as a perambulator comprising two wheeled laterally spaced panels, a single centrally disposed control handle located obliquely with reference to horizontality in a vertical plane at equal distances from the two panels, means pivotally connecting said handle with the one end of each panel whereby the laterally spaced panels are adapted to be swung through an angle of 180° between an operative position parallel to and spaced from the vertical plane containing the handle and an inoperative position in substantial register with the handle to either side thereof, a rigid transverse member removably secured to the other ends of the panels when in operative position, and abutments connected to and supported by the handle for limiting the movement of the panels at said positions.
